Primary Examiner — George D. Kirschbaum*Assistant Examiner* — Lillian Embrey(74) *Attorney, Agent, or Firm* — Dentons US LLP(57) **CLAIM**

The ornamental design for a thermostat device as shown and described.

DESCRIPTION

FIG. 1 is a perspective view of the thermostat device. FIG. 2 is a front elevation view of the thermostat device. FIG. 3 is a rear elevation view of the thermostat device. FIG. 4 is a top plan view of the thermostat device. FIG. 5 is a bottom plan view of the thermostat device. FIG. 6 is a left side elevation view of the thermostat device; and, FIG. 7 is a right side elevation view of the thermostat device. The broken lines are included for the purpose of illustrating portions of the thermostat device and form no part of the claimed design.

1 Claim, 4 Drawing Sheets(56)
